J. C. LUÉDKE,
SAFETY SIGNAL DEVICE FOR BOILERS,
APPLICATION FILED JAN. 13, 1921.

Patented Aug. 1, 1922.

2 SHEETS—SHEET 2.

UNITED STATES PATENT OFFICE.

JULIUS C. LUEDKE, OF CEDAR RAPIDS, IOWA.

SAFETY SIGNAL DEVICE FOR BOILERS.

1,424,313.

Specification of Letters Patent. Patented Aug. 1, 1922.

Application filed January 13, 1921. Serial No. 436,978.

To all whom it may concern:

Be it known that I, JULIUS C. LUEDKE, a citizen of the United States, residing at Cedar Rapids, in the county of Linn and 5 State of Iowa, have invented a new and useful Safety Signal Device for Boilers, of which the following is a specification.

This invention, which has reference to safety devices for steam boilers, is more 10 specifically designed for use in connection with locomotive boilers and adapted for actuating a signal, when the water in the boiler is so low that danger of explosion is present, and my said invention primarily 15 has for its purpose to provide a signalling means of the general character stated, that can be readily and practically applied to the common type of locomotive boiler structures, that can be manufactured at a relatively small 20 cost, easily applied for use and restored to a normal condition after having been brought into active condition for working a signal for indicating a dangerous condition of the boiler.

25 In its more specific nature, my invention embodies, in a signalling means of the kind mentioned, an improved construction of fusible member, hereinafter termed a button, so designed whereby so long as it is wholly 30 or partly submerged in the boiler water, it will not fuse, but so long as it is subjected to excessive heat from the crown sheet and within the top of the boiler, it will fuse and open up communication between the steam 35 space of the boiler and a whistle or other indicator located externally of the boiler, and thereby notify the engineer, for restoring the water level in the boiler to the desired condition.

40 Another and important feature of my invention is the provision of a simple and practical means for sustaining a group of peculiarly constructed fusible buttons so they may be readily operatively mounted within 45 the top of the boiler and in such manner that the entire outfit of fusible buttons can be expeditiously and conveniently fitted in connection with a whistle or other like signalling device, external of the boiler, and adapted 50 for being quickly disconnected from the whistle and removed from within the boiler, when it is desired to replace one or more of the fuse buttons.

Furthermore my invention, in its complete make-up, comprises an improved 55 means, in a signalling system of the char-

acter stated, that embodies a tubular steam member adapted for being connected with a whistle device external of the boiler and with which are removably joined a plurality of 60 fusible buttons that are so held within the boiler, between the usual wagon top and crown sheet members thereof, whereby to so position the fusible button, with respect to 65 and along the top of the crown sheet, so that the act of signalling is not effected during a temporary backing away of the water level at the ends of the crown, occurring during sudden end shocks, when the engine hits hard against the train of loaded cars, which 70 makes the water fly way up on either end of the crown sheet, and frequently momentarily exposes the crown sheet on one end or the other, at which times, it would not be practical to signal; the button while held in close 75 relation to the crown sheet being so formed that the spaces where the buttons are positioned over the crown sheet must get perfectly dry and hot for a short while (a minute or two), before the buttons will fuse and 80 provide for giving the signal.

With the above objects in view and other minor objects hereinafter apparent, my invention embodies, in a boiler signalling means, the peculiar features of construction 85 and novel arrangement of fusible buttons and means cooperative therewith for sustaining them in operative relation with the boiler top and the signalling device, that will be fully set out in the following detailed description, specifically mentioned in the appended claims and as illustrated in the accompanying drawings, in which:

Figure 1 is a longitudinal section of my improved boiler signalling means, so much 95 of a boiler construction (which, per se, forms no part of my invention) being shown necessary to illustrate a practical application of my invention.

Figure 2 is a transverse section thereof, 100 taken substantially on the line 2—2 on Figure 1.

Figure 3 is a perspective view of one of the improved buttons hereinafter specifically mentioned.

Figure 4 is a horizontal section of one of the said buttons, taken on the line 4—4 on Figure 2.

1 designates a pipe section or tubular member adapted to be inserted through an opening in the back head sheet 3 of the boiler into the space above the crown sheet. The

forward end of the tubular member is closed by a suitable cap and the other open end thereof is adapted to be projected through the opening 2 in the back head sheet 3 so as 5 to be connected with a whistle device in a manner presently described.

A number of fusible buttons 4 are detachably connected to the said tube, three of such buttons being shown and connected one at 10 the forward end, one at the other end of the crown sheet and one midway of the said crown sheet, as is clearly shown in Figure 1, by reference to which it will be noted the central button 4 stands a little higher 15 on the crown sheet than the two end ones and this can be readily provided for by threading the center button further into the tube 1 and by heating the crown sheet and raising it one-fourth of an inch higher where 20 the center button stands, the reason for which will be hereinafter explained.

The buttons 4, one of which is shown in detail in Figures 3 and 4, are each composed of a body made of pure soft copper and 25 provided at its upper end with a threaded shank 40 for threading into a threaded aperture 10 in the tube 1 with which the said button may be connected, steam tight, by threading it up against a washer 5 of suitable yielding material.

Centrally the body 4 is provided with a bore 41 that extends the full length thereof and which has the lower end widened or countersunk, as at 42, to receive the head 35 portions 60 of a solder filling or plug 6, the said head 60 and the bottom of the button forming a surface of considerable area for seating directly over and in contact with the top of the crown sheet 7.

40 The bottom of the button, which terminates in a circular head, and the head portion of the solder, are formed with transverse horizontal apertures 8-8 that bisect each other, see Figure 4, and which form 45 water passages for keeping the solder wet so long as the water level is above the said apertures or passages 8 and which form inlets through which the steam enters and passes through the vertical passage 41 in the button, when the solder filling melts and 50 thereby provides for an outflow of steam through the tube 1 to the whistle devices, presently explained.

The solder, in my signal button, is melted 55 from the heat of the copper casing or body 4 that surrounds it but to effect the melting of the solder, the button must stand perfectly dry before it will do this, since as long as the button stands in the water, even 60 at a one-sixteenth of an inch depth, it will transfer the heat into the water; the minute the button gets dry, it will transfer the heat to the solder metal and the latter will fuse at once and make a passage for the steam from 65 the boiler to the whistle, or other like de-

vice that will make a noise and give the signal that the water is low in the boiler.

It will be noticed from Figures 1 and 2 of the drawings, my form of button is not 70 screwed into the crown sheet or in any manner connected with the same and the bottom of the button, including the solder filling, is provided with inverted V-shaped grooves 9-9 that extend crosswise of the full diameter of the bottom.

75 These grooves 9 are provided to give the hot bubbles, that form between the button bottom and the crown sheet, better chance to escape and thereby keep the bottom and the opposing crown sheet surface perfectly 80 clean, as the small bubbles shoot out very fast, so mud will have no chance to settle under or between the buttons and the crown sheet.

The four transverse passages 8 will also 85 automatically cleanse, when acting as water spaces, for keeping the solder immersed.

In practice, the opening 2 in the back head sheet 3 of the boiler is large enough to easily 90 permit of the necessary insertion or removal of the pipe 1 with the buttons attached thereto, as the case may be, and in order to close the said opening, steam-tight, and at the same time provide a supporting medium for the tube end and the signaling device, 95 I employ a slightly tapered screw plug 12 having a nut flange 13, a circular opening 11 for the pipe 1 and an internally threaded bore 14. A washer 15, of rubber, or other suitable material, is inserted into the bore 100 14 and around the projecting end of the pipe 1 and an externally threaded follower plug or gland 16 is threaded into the said bore 14 in such manner as to cause the said washer 15 to compress and provide a steam-tight engagement with the pipe 1. The follower plug 16 is also provided with a nut flange 17 which is internally threaded at 105 18 to provide a connecting medium for the stem 19 of the combined cutoff valve and the 110 whistle device 20.

As before stated, the solder, in my construction of signal button, does not melt at the instant it comes into contact with steam. This makes my device especially desirable 115 for use in connection with locomotive boilers, in which, at times, when running the engine, the condition of the train load causes the bumping of the engine and makes the water leave one end or the other of 120 the crown sheet.

To provide for the water level conditions incident to sudden train shock, I have provided three separate buttons, one for each 125 end of the crown sheet and one for the middle and these are so disposed that it prevents all three of the buttons to give the signal at once, as the space where each button stands must be perfectly dry at least for a minute or two before giving the signal. 130

If the water level should fall to a position just high enough not to operate the middle button by uncovering the crown sheet beneath it when the train is running 5 on a level, as soon as the locomotive starts down or up a grade it may uncover the ends 10 of the crown sheet or those portions under the front or back buttons due to the inclination of the boiler and when this occurs, the end ones of the series of buttons will function.

This length of time it will not harm the crown sheet and will not be dangerous for the engineer to open the injector and to fill 15 the boiler.

As before stated the crown sheet under the central button is raised and the said central button stands somewhat higher on the crown sheet than do the end buttons, the

20 reason for which is explained as follows:—

Most of the crown sheets in boilers are as high in the back as in the front, that is,—they are as level as the water and hence if the crown sheet were not raised at a point 25 midway the ends thereof, the water level, as it lowers toward the crown sheet, would get down below all of the buttons at the same time and, in all probability, thereby cause all of the buttons to fuse at once, 30 which is to be avoided, since that entails unnecessary expense.

By raising the crown sheet and setting the central button higher than the button at the opposite ends, as the water goes down 35 lower on the crown sheet, the central button being higher, gets dry first and fuses while the end buttons still remain water submerged. The fusing of the central button will enable the engineer to feed water into 40 the boiler and raise the water level before the end buttons can fuse and thus effect the saving of the end buttons for future service.

From the foregoing description taken in 45 connection with the drawings, the complete construction, the manner of its application and use and the advantages of my invention, will be readily apparent to those familiar with the care of locomotive boilers.

50 What I claim is:

1. In a low water indicating system, the combination with a signaling element

located externally of the back head sheet of the boiler, the said element including an externally threaded member, the said head having an opening located between the crown sheet of the boiler and the top of the boiler casing; of a tubular member insertable through the opening in the said back head of the boiler, the said member being closed at one end, coupling devices engaging the externally threaded member of the signaling element and the open end of the tubular member, the said coupling devices constituting a closure for the opening in the aforesaid back head of the boiler, and a fusible button having a steam-tight connection with the tubular member and supported therefrom to position the lower end in close relation to the aforesaid crown sheet.

2. In a safety signaling means of the character described, the combination with the boiler casing having an opening in one end located above the crown sheet level of 75 the boiler; of a tube closed at one end and carrying fusible signal buttons, each of the said buttons having a passage through it that is normally closed by a fusible material, which passage when clear, opens into the 80 tube, the said tube with its buttons being insertable, closed end first, through the opening in the boiler casing end, a steam actuated signal and means connecting the tube, after it is inserted into the boiler casing 85 above the crown sheet, and the steam actuated signal, the said means constituting a steam-tight closure for the opening in the boiler end, and for sustaining the tube with the fusible signal buttons in close contact with the boiler crown sheet.

3. In a safety signal means of the character described, the combination with the boiler having a head sheet and a crown sheet, of a pipe, fusible signal buttons carried by said pipe to lie in proximity to the top of the crown sheet and extending radially from the pipe, said head sheet having an opening of a diameter large enough to permit introduction of said pipe and the 100 fusible signal buttons carried thereby and removable means for sealing said pipe in said opening.

JULIUS C. LUEDKE.
